COIN ACTUATED CALENDAR BANK

Glenn E. Woodmark, Milwaukee, Wis., assignor
to John E. Gaulke, Milwaukee, Wis.

Application July 15, 1939, Serial No. 284,664

3 Claims. (Cl. 194—1)

This invention relates to savings banks and more particularly to coin actuated calendar banks.

The primary object of the present invention resides in the provision of a new and improved coin actuated calendar bank designed to encourage the habit of systematic saving by requiring the daily deposit of a coin to maintain the calendar up-to-date.

A further object of the invention resides in the provision of a coin actuated calendar bank having ornamental qualities which adapt it to serve as a slight accessory on a wiring desk or other piece of furniture.

Another object of the present invention resides in the provision of the coin actuated calendar bank which is neat in appearance, simple in construction, positive in operation, and inexpensive to manufacture.

Another object resides in the provision in a bank of new and improved coin actuated mechanism adapted to index a date or month disc, retain the same in indexed position, and insure against accidental displacement of the disc.

A further object resides in the provision of means on the coin actuated lever adapted to overlie a portion of a coin receiving slot in order to insure its proper actuation to index a rotatable disc carrying date or month indicia upon the deposit of a coin into the bank.

A further object resides in the provision of resilient means adapted to normally retain the date and month discs in parallel spaced relationship and facilitate the operation of the coin actuated lever in performing its function of indexing the disc to advance the same upon the deposit of a coin into a receiving slot in the bank.

Other objects and advantages will become manifest from the following description of an illustrative embodiment of the present invention shown in the accompanying drawing.

In the following drawing:

Figure 1 is a front elevational view of a coin actuated calendar bank, constructed in accordance with the teachings of the present invention, having a part of the casing broken away to show the indexable date and month discs;

Fig. 2 is a vertical sectional view through the bank taken on the line 2—2 of Fig. 1;

Fig. 3 is a rear elevational view of the bank shown in Fig. 1, with parts broken away to illustrate the relative positioning of the several elements;

Fig. 4 is a horizontal sectional view on the 55

line 4—4 of Fig. 3, illustrating the action of a coin upon the indexing lever as the coin is inserted through the coin receiving slot in the casing of the bank;

5 Fig. 5 is a horizontal sectional view of the coin actuated lever taken on the line 5—5 of Fig. 3 showing the lever fulcrum together with the latching mechanism for retaining the date disc in indexed position;

10 Fig. 6 is a detail view taken on the line 6—6 of Fig. 3 showing the disc engaging foot on the coin actuated indexing lever in contact with a tooth on the month disc; and

Fig. 7 is a detail sectional view taken on the 15 line 7—7 of Fig. 3 showing the disc engaging foot on the coin actuated lever in contact with a tooth on the date disc.

In the embodiment of the new and improved coin actuated calendar bank chosen for illustrative purposes in the accompanying drawing, the bank comprises a casing 10 preferably formed of molded plastic material to provide an inexpensive article of ornamental coloring. To enhance the appearance of the bank it will be noted that it is provided with gracefully rounded corners to present an article of pleasing appearance in addition to its utilitarian purpose which combines that of a calendar and a savings bank.

30 The face of the bank is provided with windows 11 preferably disposed in horizontally spaced relationship to one side of the center of the bank and approximately mid-way between the top and the bottom thereof. A plurality of parallelly disposed coin receiving slots 12, 13 and 14 formed in the face of the casing 10 provide means for respectively receiving quarters, nickels and dimes. This series of coin receiving slots is disposed adjacent the upper left hand corner of the casing to provide a convenient location for inserting any one of the selected coins to effect the indexing of the day disc to advance the calendar date reading one number. A similar coin receiving slot 15 is disposed adjacent the upper

45 right hand corner in the face of the bank to permit the insertion of a coin, in the present instance a quarter, to effect the indexing of the month disc on the first day of each succeeding month. The top face of the case 10 is provided with a coin receiving slot 16 adapted to receive coins of any denomination or folded bills. Money deposited through the slot 16 may be termed "a conscience fund" as it is deposited directly into a coin receiving compartment and does not contact coin actuating mechanism to

50

effect the indexing of either the day or month disc of the calendar.

The rear edge of the molded plastic casing 10 is provided with a seat 17 adapted to receive a removable cover 18 which forms a closure for the bank. The casing is provided with integrally formed bosses 19 adjacent the several corners to provide an abutment for a partition element 20 which divides the casing into two compartments, a relatively small mechanism compartment 21 and a relatively large coin compartment 22. The casing is further provided with a substantially centrally disposed inwardly projecting cylindrical boss 23 which serves as a mounting means for an indexable month disc 24 and an indexible date disc 25. The two discs 24 and 25 are formed of thin sheet metal and are loosely journaled on the boss 23 and are retained in spaced relationship by a spring finger washer 26. A spacing washer 27 is adapted to surround the boss 23 and lies between the date disc 25 and the partition 20. A boss 28 also preferably formed integral with the casing 10 serves as a fulcrum on which a coin actuated lever 29 adapted upon movement to index the date disc is journaled for rockable movement. The lever 29 is provided with a sleeve 30 which forms a bearing for contact with the boss or pin 28. The lever is also provided with an offset upper portion 31 adapted to lie adjacent the partition 20. The forward edge of the offset portion 31 is directed toward the inner wall of the casing 10 to provide a coin contacting flange 32. A tongue 33 is struck from the flange 32 to provide an anchoring means for one end of a coil spring 34; the other end of which is anchored on a pin 35 also preferably formed integral with the casing 10. It will be noted that the coil spring 34 lies in a recess 36 molded in the casing 10. Partitions 37 lying between and adjacent the several slots 12, 13 and 14 are also molded in the casing 10 and terminate short of one end of the several slots to form abutment faces 38 against which the coin contacting flange 32 of the lever 29 is retained by action of the coil spring 34. It will be noted that the flange 32 underlies a portion of each slot so that a coin cannot be inserted through any of the slots without effecting a rocking action of the lever 29 on its fulcrum pin 28. If a coin of any chosen denomination is inserted through its respective slot, the coin actuated lever 29 is rocked in a counterclockwise direction (referring to Fig. 3) to effect the retracting of a disc propelling tang 39 turned outwardly from the lower extremity of the arcuately formed lever 29 from one tooth 40 formed in the peripheral edge of the day disc 25 and cause it to move laterally past the next succeeding tooth 40 to engage that tooth to propel the disc in a clockwise direction upon release of the coin from contact with the flange 32 of the lever 29 as the coin drops into the coin compartment 22 to effect the indexing operation to bring the next succeeding number into visible position through the window 11 formed in the casing. As the lever 29 is rocked under action of a coin, an angularly disposed cam surface 41 formed on the tang 39 will contact the next succeeding tooth 40 and cause the disc 25 to rock from its normal vertical position against the action of the spring finger disc 26 that yieldably retains the disc 25 in a vertical position but permits a slight rocking of the disc laterally under the action of the lever 29. After the tang 39 has passed the next succeeding

tooth 40 the spring disc 26 will cause the day disc to reassume its normal position parallel to the inner wall of the casing 10. The coin actuated lever 29 is provided with a second outwardly extending tang 42 adapted to pass in front of and contact one of the teeth 40 to prevent forward rotating movement of the disc when the arm 29 lies in its normal position. A cooperating tang 43 is also struck from the lever 29 at a spaced distance from the tang 42. The tang 43 contacts a similar tooth 40 to prevent rearward rotating movement of the disc 25 when the lever 29 is in its normal position. Upon insertion of a coin to actuate the lever 29, the tang 42 will spring upwardly and outwardly from the center of the disc 25 with the movement of the lever 29 to clear the edge of the tooth and disc to permit the indexing operation and the next succeeding tooth adjacent the tang 43 will pass freely over the rounded portion of the tang 43 and drop into contact with the edge thereof to effect the latching operation at such time as the coil spring 34 returns the lever 29 to its inactive position as the coin leaves the slot under pressure of the person's finger and drops into the coin compartment 22. It should be noted at this point that the several teeth 40 provide thirty-one equally spaced divisions about the periphery of the disc 25. Each of these thirty-one divisions has aligned therewith a numeral corresponding to the respective days of the month so that the insertion of the nickel, dime or quarter will effect a single indexing operation to advance the date one number.

A coin actuated lever 44, adapted to effect the indexing of the disc 24, is rockably mounted on a pin 45, preferably formed integral with the casing 10. The lever is provided with an offset upper portion 46 and a flanged portion 47 which lies in contact with an abutment 48 formed by the end of the side walls adjacent one end of the slot 15. A coil spring 49 has one end anchored to the flange 47 formed on the upper portion of the arm 44 and its other end is anchored on a pin 50 preferably formed integral with the casing 10. The coil spring 49 lies in a recess 51 formed in the casing 10. The lower extremity of the arm 44 terminates in an outwardly extending tang 52 for normally lying in contact with one of the teeth 53 formed in the periphery of the month disc 24. Upon the insertion of a quarter in a slot 15, the coin actuated arm 44 is rocked in a counterclockwise direction (as shown in Fig. 3) to effect the withdrawal of the tang 52 from one tooth and retract it to a position where it will contact the next succeeding tooth. As the coin passes from contact with the flange 47, the arm 44 will swing in clockwise direction to effect the indexing of the month disc to bring the next succeeding month designation beneath the window 11 formed in the face of the casing 10. The tang 52 is provided with a cam surface 54 which contacts the next succeeding tooth to effect a slight rocking action of the disc 24 against the action of the spring fingered element 26, as the lever 44 is rocked in a counterclockwise direction under the action of a coin.

When the lever 44 rocks, it moves the tang 52 laterally past the next succeeding tooth 53, and the element 26 will move the disc 24 back to its normal position, in which the tang 52 will contact the next succeeding tooth 53 on the periphery of the disc 24 to effect indexing of the disc 24. The arm 44 is provided with a tang 55 which

contacts one side of a tooth 53 formed in the periphery of the disc 24. A cooperating tang 56 is struck from the lever 44 in spaced relationship with the tang 55 in a manner to engage the opposite face of the tooth 53 to normally retain the disc 24 against accidental displacement from its indexed position.

A plurality of spring fingers 51 are imbedded in the casing 10 in a manner to extend into the slot 46 formed in the upper wall of the casing. The spring fingers 51 serve to prevent the withdrawal of any coin from compartment 22 after the same has been inserted therein.

Suitable cap screws 58 may be employed to retain the partition 20 in position upon the boss 19 formed in the casing 10.

A rod 59 is provided with reduced threaded portion 60 adapted to be received through a hole 61 formed in the partition 20 and threaded into an aperture 62 formed in the casing 10. The outer extremity of the rod 59 is provided with a rounded head portion and a reduced neck portion 63 lying adjacent to the head. The rod 59 forms an anchoring means for the cover 18 which carries a cage 64 in which a locking bar 65 is slidably mounted. The cage 64 is provided with hole 66 of sufficient size to receive the head of rod 59. The locking bar 65 is provided with a bayonet which will also receive the head of rod 59 as the back is pressed into position on the casing 10. When the cover portion 18 is in proper position, a coil spring 67 which surrounds a tail rod 68 formed on the bar 65 will urge the bar 65 to its upper or locking position to retain the cover securely upon the casing 10. A slot 69 adapted to receive a key (not shown) provides a means for unlocking the bank by compressing the spring 67 to depress the bar 65 and effect the unlocking operation by releasing the locking engagement between the bar 65 and the neck 63, to permit the cover 18 to be withdrawn from the casing 10 to expose the coins in the coin compartment 22.

While the structure and operation of the coin actuated calendar bank has been described in considerable detail, it is deemed advisable to mention a few of the advantages flowing from the embodiment of the present invention.

In the objects set forth in this application mention was made of the provision of a new and improved coin actuating calendar bank having a low manufacturing cost. This statement is borne out by the fact that the several operating mechanisms are each formed of a sheet metal stamping, the cost of which is extremely low. It will also be noted that the manner of assembly of the several elements is extremely simple and since the casing comprises a molded plastic material which requires no machining, it will readily be understood that the production of this bank is extremely simple and of minimum cost.

The main purpose of providing an inexpensive, artistic and useful article of the nature of the present invention, is to encourage the systematic saving of sums of money, and it is contemplated that the coin actuated calendar bank will be made use of by banking institutions, credit unions, saving associations and individuals to the mutual advantage of all concerned.

While the invention has been described in considerable detail in the foregoing specification it is to be understood that various changes may be made in its embodiment without departing

or sacrificing any of the advantages hereinafter claimed.

I claim:

1. A coin actuated calendar bank comprising, a casing, a window in the face of said casing, a coin receiving slot in the face of said casing, a partition in said casing disposed parallel with the face of said casing whereby said casing is divided into a relatively thin mechanism compartment and a relatively spacious coin compartment, an indexable disc rotatably mounted in said mechanism compartment and disposed to normally lie parallel to the inner face of said casing, a plurality of equally spaced teeth formed in the periphery of said disc, indicia on the side of said disc adjacent the casing adapted to successively register with said window, a spring disposed to contact said disc and normally maintain it in parallel relationship with the inner wall of said casing, a coin actuated disc indexing lever rockably mounted in said mechanism compartment and disposed to lie parallel to said disc, a tooth contacting tang formed on the free end of said lever disposed adjacent the periphery of said disc, a coin contacting surface on said lever disposed to overlie a portion of said coin receiving slot, an abutment adapted to limit the movement of said disc indexing lever in one direction, and a second spring for normally maintaining said lever in abutment contacting position whereby the insertion of a coin through said slot causes said disc indexing lever to rock about its pivot against the action of said last mentioned spring to effect the displacement of said disc from its normal vertical position against the action of said disc contacting spring by the movement of said tang from contact with one tooth on said disc to the next succeeding tooth, said second spring being cocked by the movement of said lever to an extent that the passing of the coin from contact with said lever results in the advance of the disc under action of said tang as said lever is returned to its normal abutment contacting position under the action of the said second spring.

2. A coin actuated calendar bank comprising, a casing, a window in the face of said casing, a coin receiving slot in the face of said casing, a partition in said casing disposed parallel with the face of said casing whereby said casing is divided into a relatively thin mechanism compartment and a relatively spacious coin compartment, an indexable disc rotatably mounted in said mechanism compartment and disposed to normally lie parallel to the inner face of said casing, a plurality of equally spaced teeth formed in the periphery of said disc, indicia on the side of said disc adjacent the casing adapted to successively register with said window, a spring disposed to surround the central portion of said disc and contact the same to normally maintain said disc in parallel relationship with the inner wall of said casing, a coin actuated disc indexing lever rockably mounted in said mechanism compartment and disposed to lie parallel to said disc, a tooth contacting tang formed on the free end of said lever disposed adjacent the periphery of said disc, additional tang means on said lever adapted to engage teeth on the periphery of said disc to normally retain said disc against accidental indexing movement, a coin contacting surface on said lever disposed to overlie a portion of said coin receiving slot, an abutment adapted to limit the movement of said disc indexing lever in one

direction, and a coil spring for normally maintaining said lever in abutment contacting position whereby the insertion of a coin through said slot effects the rocking action of said disc actuating lever against the action of said coil spring and thereby effects the retraction of the tang means from their normal disc retaining position, and simultaneously effects the displacement of said disc from its normal vertical position against the action of said disc contacting spring by the movement of said tooth contacting tang formed on the free end of said lever disposed adjacent the periphery of said disc from contact with one tooth of said disc to the next succeeding tooth on said disc, the movement of said disc indexing lever serving to cock said coil spring, and said coil spring serving upon passage of the coin from contact with said disc indexing lever to index said disc under action of said last named tang upon return movement of said disc indexing lever to its normal inactive position.

3. A coin actuated calendar bank comprising, a casing, a window in the face of said casing, a coin receiving slot in the face of said casing, a partition in said casing dividing the same into a relatively thin mechanism compartment and a relatively spacious coin compartment, said partition being disposed parallel with the face of said casing, an indexable disc rotatably mounted in said mechanism compartment and disposed to normally lie parallel with the inner face of said casing, a plurality of equally spaced teeth

formed in the periphery of said disc, indicia on the face of said disc disposed toward the casing and adapted to successively register with said window, a spring disposed to surround the central portion of said disc and contact the same to normally maintain it in parallel relationship with the inner wall of said casing, and a coin actuated disc indexing lever rockably mounted in said mechanism compartment and disposed to lie parallel to said disc, a coin contacting surface on said lever disposed to overlie a portion of said coin receiving slot, a tooth engaging tang on said lever adapted upon movement of said lever to engage successive teeth on said disc, an abutment on the inner wall of said casing adapted to limit the movement of said lever in slot overlying position, a spring for normally retaining said lever in abutment contacting position whereby the insertion of a coin in said coin receiving slot effects the indexing operation of said disc through the sole action of said disc indexing lever which successively effects the displacement of the disc from its normal position to permit the movement of the tooth engaging tang from contact with one tooth to the next successive tooth, cocks the spring for returning said lever to its normal inactive position, and effects the indexing operating of said disc upon the return movement of said lever after the coin has passed from contact with said disc indexing lever.

GLENN E. WOODMARK
